Ergodyne—Slip On Spikeless Traction Devices, announced Aug. 6, 2020 [online], [site visited Jun. 12, 2022]. Available from internet, URL: <https://www.amazon.com/Ergodyne-Spikeless-Traction-Devices-Outdoor/dp/B08FCXWX27?th=1> (Year: 2020).*Primary Examiner — Leanne Was-Englehart*Assistant Examiner* — Yelizaveta Y Masalimova(74) *Attorney, Agent, or Firm* — Skaar Ulbrich Macari, P.A.(57) **CLAIM**

The ornamental design for a multi-surface traction sling, as shown and described.

DESCRIPTION

FIG. 1 is a perspective view of a multi-surface traction sling showing our new design.

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The footwear shown in FIG. 1 forms no part of the claimed invention. The broken lines shown in FIG. 7 represent stitching and form a part of the claimed invention.

1 Claim, 7 Drawing Sheets
